US00D927671S

(12) **United States Design Patent** (10) **Patent No.:** **US D927,671 S**
(45) **Date of Patent:** **** Aug. 10, 2021**

(54) **AIR PURIFIER**(71) Applicant: **ACCO Brands Corporation**, Lake Zurich, IL (US)(72) Inventor: **Seesong Kang**, Northbrook, IL (US)(73) Assignee: **ACCO Brands Corporation**, Lake Zurich, IL (US)(***) Term: **15 Years**(21) Appl. No.: **29/770,071**(22) Filed: **Feb. 9, 2021****Related U.S. Application Data**

(62) Division of application No. 29/653,118, filed on Jun. 12, 2018, now Pat. No. Des. 913,467.

(51) **LOC (13) Cl.** ..... **23-04**(52) **U.S. Cl.**USPC ..... **D23/364**(58) **Field of Classification Search**

USPC ..... D23/355-366, 352, 369, 332, 333, 335, D23/336, 342, 351; 422/120, 122; 55/356, 473, 504; 96/97; 261/DIG. 17, 261/DIG. 65, DIG. 88, DIG. 31 CPC .. A61L 9/16; A61L 9/22; B01D 47/00; B01D 47/027; B01D 2221/02; B01D 2259/4508; B03C 3/155; B03C 3/368; F24F 3/16; F24F 13/20; F24F 13/28

Primary Examiner — David G Muller(74) *Attorney, Agent, or Firm* — Fitch, Even, Tabin & Flannery, LLP(57) **CLAIM**

The ornamental design for an air purifier, as shown and described.

DESCRIPTION

FIG. 1 is a front perspective view of our new design of an air purifier;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines illustrate certain features that are shown for illustrative purposes only and do not constitute any part of the claimed design.

1 Claim, 7 Drawing Sheets# US D927,671 S
